ASSIGNORS TO THE CONSOLIDATED EXPANDED METAL COMPANIES, OF WHEELING,
WEST VIRGINIA, A CORPORATION OF WEST VIRGINIA

METALLIC EDGING

Application filed April 12, 1928. Serial No. 269,396.

This invention relates to metallic edging, such, for example, as is useful for sashing for screens, gratings, guards, grilles, and the like, especially where material such as metallic 5 fabric or lath is employed.

One of the primary objects of the invention is to provide a standard form of edging which is capable of a wide variety of applications.

Another object of the invention is to provide edging which affords maximum rigidity and strength with a minimum weight of metal.

Other objects and advantages will appear in the accompanying description of the preferred form of our invention which is illustrated in the drawings, wherein—

Fig. 1 is a diagrammatic side elevation of a screen employing our invention, and

Figs. 2 to 11 inclusive are fragmentary 20 cross sectional views illustrating a number of different ways in which the invention may be applied.

Referring now to Fig. 1, the reference numeral 7 may be taken as representing a frame 25 such as a window frame, and the reference character A denotes the screen or similar member to be mounted in said frame.

The screen comprises a frame or sash constructed from the edging to be described and 30 the metal fabric 8.

The edging employed in constructing the screen frame is shown in Figs. 2 to 11 inclusive, and is made from sheet metal pressed into substantially U-form in cross section, the 35 legs 9 of the U being spaced sufficiently closely together to just about receive the particular type of metal fabric that is employed. The base of the edging is in the form of a bulb 10 in cross section. Four lengths of the 40 edging are employed, the frame being completed by the brackets 11 at the corners.

It will be seen that the cross sectional form of the edging is one which is calculated to 45 secure maximum strength and rigidity with a minimum weight of metal. The provision of the bulb also secures a number of other advantages, one of the most important of which is that the hinges or other means employed in fastening the screen frame may 50 be attached to the screen frame in a number

of different ways or places. Thus, for example, in Fig. 2 the hinge 12 has one leaf rounded as indicated at 12^a this leaf being secured to the inside of the screen frame, the other leaf being secured to the face of the main 55 frame 7. In Fig. 3 the leaves of the hinge are secured, respectively, to the adjacent faces of the screen frame and the frame 7.

It is often necessary to secure two or more frames together. Fig. 4 shows one way in 60 which two adjacent screen frames may be hinged together. Fig. 5 illustrates another way, while in Fig. 6 there is illustrated a way of hinging two screen frames together where the screens normally extend at right 65 angles to one another. Another way of hinging two screen frames is illustrated in Fig. 8 wherein there is attached to the bulb portion of the adjacent frames a clip 13, one leg of which is rounded to engage the bulb, and the other leg of which is straight. A hinge 14 has its leaves secured to straight legs 13 of the respective clips.

In Figs. 7 and 9 we have illustrated how 70 clips 13 may be employed to secure screen frames together, either where the screens extend in the same plane or extend in planes at right angles to one another.

In Figs. 10 and 11 we have illustrated 75 different ways in which the clips 13 may be employed to secure the screen frames to the main frames.

We prefer to secure the leaves or legs of the edging to the bulb by means of hardened metal screws 15. To this end we drill 80 holes in the bulb portion of the edging at appropriate places, these holes being of slightly smaller diameter than the screw, in consequence of which the screw taps its own 85 thread in the bulb.

It will be seen from the foregoing that a 90 relatively small number of standard attaching means are all that are needed to make it possible to apply the screens or gratings in a variety of different ways.

The metal fabric may be secured between the legs of the edging in a number of different ways. Inasmuch as, in most cases, the screen or grating will be galvanized, the 95 spelter will bond the fabric and the edging 100

together. In order to permit excess spelter to run out of the edging, holes 16 are provided in the brackets 11. In the absence of such holes, the edging may become solidly filled with spelter which would be uneconomical and also result in excess in weight which would be objectionable. Where the screen or guard is not to be galvanized, screws 15 may be employed to secure the fabric between the legs of the edging.

10 We claim:

1. A screen comprising a frame, metallic fabric secured to the frame, said frame being composed of U-shaped metallic edging with the base in the form of a cylindrical bulb in cross section, and attaching means comprising a two-winged member, one wing of which is adapted to be secured to an adjacent structure, and the other wing being curved on the same radius as the bulb and having a width such that it is adapted to embrace approximately one-half of the bulb circumferentially, and means for securing said curved wing member to the bulb portion.

2. A screen comprising a frame, metallic fabric secured to the frame, said frame being composed of U-shaped metallic edging with the base in the form of a cylindrical bulb in cross section, and attaching means engaging the bulb comprising a two-winged hinged member, each of the wings of which is curved on the same radius as the bulb and having a width such that each is adapted to embrace about half of a bulb circumferentially, and means for securing the said two wings to bulb portions.

3. A screen comprising a frame, metallic fabric secured to the frame, said frame being composed of U-shaped metallic edging, with the base in the form of a cylindrical bulb in cross section, and attaching means comprising a two-winged member, each wing of which is curved on the same radius as the bulb and having a width such that it is adapted to embrace approximately half of the bulb circumferentially, and means for securing said wings to bulb portions.

In testimony whereof we have hereunto signed our names.

THOS. R. HERBEST.
CHAS. J. HOFFMAN.
